(57) **CLAIM**

The ornamental design for surface ornamentation for a container, as shown and described.

DESCRIPTION

The present application file contains at least one drawing executed in color. Copies of this patent or patent application publication with color drawing(s) will be provided by the Office upon request and payment of the necessary fee. The sole FIGURE is a front view of the surface ornamentation for a container embodying our new design. The broken lines are included herein for illustrative purposes only and form no part of the claimed design.
